ARTICLE TRANSFER MECHANISM

Walter E. Heise, Syracuse, N. Y.

Application November 9, 1948, Serial No. 59,042

7 Claims. (Cl. 198—20)

1

This invention relates to machines for freezing confections, and has for its object a motion transmitting mechanism between a prime mover and a carrier by which moulds containing a fluid confection are lowered into the freezing chamber at the receiving end of the machine, and between the prime mover and a feed or pusher element which moves the moulds intermittently from the carrier through the freezing chamber to a discharge station with one mould abutting against a preceding mould that has been lowered by the carrier into the freezing chamber, which mechanism comprises a differential gearing actuated by the prime mover and including motion transmitting connections between the shafts of the side gears of the differential and the carrier and the pusher respectively. As is well known, one of the characteristics of a differential gearing is that if one of the side gears is restrained, or stopped, the motion is transferred to the other side gear and hence, when the pusher is restrained from movement, the carrier will be actuated, and when the movement of the carrier is stopped, the pusher will be actuated.

In the mechanism of this invention, the pusher remains idle when the operating lever is operated to set the mechanism in motion, because the weight of the carrier and moulds thereon tends to cause the carrier to lower by gravity into the freezing chamber and hence, the path of least resistance is through the side gear of the differential controlling the raising and lowering of the carrier. The pusher may be restrained by the carrier when the carrier is in its upper position. When the carrier carries the moulds fully into the freezing chamber, the carrier is restrained from further movement and hence, the pusher is actuated from the other side gear of the differential to push the moulds from the carrier through the freezing chamber. Preferably, in this machine means are provided for timing and controlling the operations of the pusher and the carrier from the side gears of the differential gearing.

The invention consists in the novel features and in the combinations and constructions hereinabove set forth and claimed.

In describing this invention, reference is had to the accompanying drawings in which like characters designate corresponding parts in all the views.

Figure 1 is a plan view of a machine embodying this invention.

Figure 2 is a side elevation, partly broken away.

2

Figure 3 is a sectional view on line 3—3, Figure 2.

Figure 4 is an enlarged plan view, partly broken away, on line 4—4, Figure 2.

Figures 5, 6, 7 and 8 are fragmentary detail views of mechanism shown in Figure 4 on lines 5—5, 6—6, 7—7 and 8—8.

Fig. 9 is an elevation, partly in section, of the control valve mechanism for the prime mover.

10 Figure 10 is an enlarged sectional view on line 10—10, Figure 1.

This machine for freezing confections comprises generally a freezing chamber 1, a carrier 2 shiftable vertically to carry moulds 3, which contain a fluid confection to be frozen, into the freezing chamber at a receiving station, or end of the machine, a feed or pusher mechanism including a push bar 5 for pushing the moulds horizontally off the carrier, when the carrier is in lowered position, through the freezing chamber to a discharge station, or end of the machine, the moulds on the carrier abutting against moulds previously shifted off the carrier so that a series of moulds are progressed intermittently through the freezing chamber, each mould abutting or pushing against the preceding mould, and actuating mechanism for alternately actuating and timing the actuation of the carrier and the pusher, which mechanism includes a differential gearing.

20 The freezing chamber 1 is usually a brine tank having tracks 4 along which the moulds are pushed after being pushed off the carrier. These tracks may incline upward at the discharge end of the machine so that the moulds, with the frozen confection therein, are lifted out of the freezing chamber at the discharge end of the machine by the progressing action of the moulds.

The carriage 2 comprises transversely spaced frame plates 6, here shown as angular in elevation and each having lower horizontal arms 7 between which a bottom plate 8 is mounted. The frame plates divide the carrier into compartments, in each of which a mould may be placed. The moulds 3 rest on the bottom plate 8. The carrier

40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

lower the moulds vertically by gravity recti-

linearly into the freezing chamber when the operating lever is actuated to start the machine in motion. The angular shape of the plates 6 is such that the push bar moves horizontally over the bottom of the carrier and pushes the moulds off the carrier, when the carrier is in its lower position. The angular formation forms horizontal slots in which the push bar moves during its sweep over the bottom 8 of the carrier.

The pusher comprises the transverse horizontally movable bar 5 mounted at its ends in brackets 16 which depend into the tank 1 from slides 17 movable in guide channels 18 in rails 19 extending lengthwise of the top edges of the tank 1, Figure 3. The push bar 5 is arranged to push against the front ends of the moulds on the carrier, and are located at a level to push against the same when the carrier is in lowered position. The push bar 5 may be obstructed from movement by the moulds on the carrier when the carrier is in elevated position. The moulds 3 are provided with handles 20 at their front and rear ends. The handles 20 act as buffers coacting with abutments 21 on the bracket 2A to locate and align the moulds when placed on the elevated carriage. Also, the handles act as buffers to engage those of the preceding moulds when the moulds are being pushed off the carriage 6 and along the tracks 4. The prime mover is here shown as a cylinder and piston motor.

25. Figures 1 and 2, designates the cylinder, and 26 the rod of the piston movable in the cylinder, the piston rod being a reciprocating actuator. It is shown as connected at 27 to a reciprocating rack 28 extending lengthwise of the frame member 19 at one side of the tank 1 and serves as a transmitting element to transfer the motion to a differential gearing.

29 designates the differential gearing. This includes a casing 30, side gears 31 and 32, Figure 4, mounted on shafts 33 and 34 respectively, journalled in the hubs of the casing, and differential pinions 35 within the casing and meshing with the side gears. The casing 30 is provided with a gear 36 on one of its hubs which meshes with the rack 28 to receive motion therefrom. The carriage 2 is actuated from the shaft 34 of the side gear 32 and as here illustrated the shaft 34 is provided with a pulley 37 from which motion is transmitted to the carrier 2, as by a belt or chain 38 running over the pulley 37 and over a pulley 39 mounted on a transverse shaft 38A journalled in the bracket 2A, and the cables or chains 40 winding on pulleys 390 on the shaft 38A and anchored at like ends to pulleys 390, and passing over idler pulleys 41 also carried by a shaft 41A mounted in the bracket 2A, the chain being secured at its other end at 42 to the carriage, or to a transverse rod 2B extending through the upper arms of the frame plates 6 of the carriage 2. The pulleys 37 and 39 and chains 38 are triple as the chains available are comparatively small ones used in place of one large chain.

The motion of the differential is transferred to the pusher to actuate it through a pair of racks 43 movable in the guide slots 18 and connected to the slides 17, from which the pusher 5 is suspended. The racks 43 are actuated from the side gear 31 of the differential, through a gear 44, Figures 4, 5 and 6, mounted on the shaft 33 of the side gear 31 and meshing with an intermediary gear 45 which meshes with a gear 46 which, in turn, meshes with the rack 43. There are two gears 46 mounted on opposite ends of the transverse shaft 47, these gears 46 meshing

with racks 43 on opposite sides of the freezing chamber.

The outer end of the shaft 33 of the side gear 31 is journalled in a bearing plate 48, Figures 5, 1, 2 and 4, mounted on the rail 19. The shaft 34 is journalled in a lengthwise support or rail 49 suitably supported on top cross framing bars between the rails 19. The intermediate gear 45 and gear 46 are mounted respectively on a stud mounted in the bearing plate 48 and on the shaft 47 which is journalled at one end in the plate 48 and at its other end in a bearing on the other rail 19.

In the general operation, when the piston moves 15 to the right and thus rotates the differential housing 30 in one direction, the pusher bar 5 is idle, or may be restrained by the carrier when the carrier is in elevated position. Thus, the motion is transferred through the side gear 32 to rotate 20 its shaft 34 in one direction. This movement tends to rotate the differential side gear 31 in the opposite direction, but the racks 43 remain stationary, and rotary movement of the shaft 34 is transferred through the chain 38 and the chain 25 48 to the carrier 2, as this is the path of least resistance and because the carrier tends to drop by gravity into the freezing chamber. When it reaches the bottom of the freezing chamber, the side gear 32 of the differential is stopped and at 30 the same time the side gear 31 is free because the moulds have cleared the pusher 5, permitting the bar 5 thereof to move and push the moulds off the carrier through the freezing chamber. However, precautionary provisions are made to 35 stop the rotation of the shaft 34 of the side gear 32 after predetermined intervals, as will be presently described.

As here illustrated, this means comprises a nut element 50, Figure 4, on the shaft 34 and held from turning movement by an arm 51 anchored at 52 to a cross bar, this being conveniently the shaft 47 connecting the gears 46. As the shaft 34 rotates, the nut is shifted axially to the left to move a tooth 53 thereon into position where it will engage a shoulder 54 on a collar 55 keyed to the shaft 34. The collar also coacts with a latch 60, as will be presently described. A precaution is also provided against movement of the carriage 2 while the pusher is in an intermediate position in its travel, or is obstructed in its travel as, for instance, by being frozen from feeding movement, or is not in starting position. This means consists of the spring pressed latch 68 in the form of an angle lever pivoted at its 45 angle at 61 to the bracket 2A and normally pulled into engagement with a stop shoulder 62 on the collar 55 to prevent retrograde movement of the shaft 34, the latch being normally arranged in the path of the shoulders 62 on the collar 55 when the push bar is on its operating movement, as the movement to the right. However, when one of the racks 43, which actuates the push bar, approaches the limit of its movement to the left, at which time the push bar 5 is approaching 50 starting position, a pin 66 on the rack encounters an arm 67 of the latch 60 and trips the latch 60 out of its operative position into the position shown in Figures 2 and 7.

The control for the motive fluid, which is air, will now be described.

70. Figures 1, 2 and 9, designates a control valve, this being of any suitable type and including a casing having an intake at 71 for a motive fluid, as compressed air, and outlet ports 72, 73, 75 and an exhaust port 74. The valve further in-

cludes a movable valve member having transfer passages 75, 76, the latter being an exhaust passage. In the position shown in Figure 9, the parts are in the position in which the cylinder can exhaust through a pipe 80 to the left end of the cylinder through the transfer passage 76 and exhaust port 74. The valve member is operated by a handle 82 connected by a link 83, through an over-the-center spring snap valve mechanism 84, to the valve member, the link 83 being connected to a radial arm 85 on the valve member. When the handle 82 is moved to its dotted line position, Figure 9, air will enter through the inlet port 71, transfer passage 75, which is now communicating with the pipe 80, through the pipe 80, to the left end of the cylinder, so that the piston travels to the right from the position shown in Figures 1 and 2. During this movement, air exhausts from the right end of the cylinder, through pipe 90, valve mechanism designated generally 91, pipe 92, through port 73 and transfer passage 76, to exhaust port 74. During this operation, the carriage 2 is being lowered into the freezing chamber and in order to prevent it from lowering too fast and hence, to avoid the splashing of brine into the moulds, the exhaust from the pipe 90 is past a restraining orifice or needle valve 93, Figure 10, and after the piston rod has been actuated a predetermined distance to the right sufficient to fully lower the carrier 2 into the freezing chamber, a cam 95, operated by the piston rod, engages the stem 96 of a spring closed valve 97 which by-passes the needle valve and hence, opens the valve 97 fully, so that the exhaust now by-passes the needle valve and passes out without restraint. The cam 95, Figure 10, is here shown as mounted to rock on a stud 98 fixed to a bracket 99 on the casing of the valve 91, and as operated by a shoulder or lug 100 on the piston rod located to engage one radial arm 101 of a fork 102 on the stud 98 and rockable as a unit with the cam 95 when the piston has traveled part way in its movement to the right and thus fully open the exhaust valve 97 during the remainder of the stroke to the right, and to engage the other arm 103 of the fork and allow the exhaust valve 97 to close during the power stroke of the piston rod to the left. When the piston is being actuated to the left, the air enters the cylinder through pipe 92, valve 91, and pipe 90, and the valve 97 is opened (when closed) by the air pressure through the pipe 92. The cam 95 is located with respect to the stroke of the piston rod, so that the exhaust valve 97 is closed only while the carrier 2 is lowering the moulds into the freezing chamber and the pusher 5 initially pushing to move the trays off the carrier and take up the space between the trays on the carrier and the trays previously pushed off the carrier.

At the end of the movement of the piston to the right, a pin or shoulder 104, Figure 1, on one of the brackets 16 carrying the pusher 5 engages the arm 25, Figure 9, of the valve operating mechanism and shifts the valve and its handle 82 from dotted line to full line or starting position.

What I claim is:

1. In a machine for freezing confections comprising a freezing chamber through which moulds containing confections to be frozen are passed horizontally from a receiving station to a discharge station, a carriage at the receiving station shiftable vertically for lowering moulds with fluid confection therein into the freezing cham-

ber, a horizontally movable pusher at the receiving station and located to push against the moulds and move them horizontally off the carriage when the latter is in its lowered position and push the moulds against the preceding moulds pushed from the carriage, and actuating mechanism comprising a reciprocating prime mover, and motion transmitting means operable thereby to alternately operate the carrier and the pusher comprising a differential gearing which comprises a rotatable casing, side gears mounted on shafts journalled in the casing and differential gears in the casing and meshing with the side gears, motion transmitting connections between the prime mover and the casing to rotate the latter, motion transmitting connections between the shaft of one side gear and the carriage, and motion transmitting connections between the shaft of the other side gear and the pusher.

2. In a machine for freezing confections comprising a freezing chamber through which moulds containing confections to be frozen are passed horizontally from a receiving station to a discharge station, a carriage at the receiving station shiftable vertically for lowering moulds with fluid confection therein into the freezing chamber, a horizontally movable pusher at the receiving station and located to push against the moulds and move them horizontally off the carriage when the latter is in its lowered position and push the moulds against the preceding moulds pushed from the carriage, and actuating mechanism comprising a reciprocating prime mover, and motion transmitting means operable thereby to alternately operate the carrier and the pusher comprising a differential gearing which comprises a rotatable casing, side gears mounted on shafts journalled in the casing and differential gears in the casing and meshing with the side gears, motion transmitting connections between the shafts of the side gears and the differential gears, a gear mounted on the casing, a rack connected to the prime mover to be reciprocated thereby and meshing with the gear on the casing, and motion transmitting connections between the shafts of the side gears of the differential gearing and the carriage and the pusher respectively.

3. In a machine for freezing confections comprising a freezing chamber through which moulds containing confections to be frozen are passed horizontally from a receiving station to a discharge station, a carriage at the receiving station shiftable vertically for lowering moulds with fluid confection therein into the freezing chamber, a horizontally movable pusher at the receiving station and located to push against the moulds and move them horizontally off the carriage when the latter is in its lowered position and push the moulds against the preceding moulds pushed from the carriage, and actuating mechanism comprising a reciprocating prime mover, and motion transmitting means operable thereby to alternately operate the carrier and the pusher comprising a differential gearing which comprises a rotatable casing, side gears mounted on shafts journalled in the casing and differential gears in the casing and meshing with the side gears, a gear mounted on the casing, a rack connected to the prime mover to be reciprocated thereby and meshing with the gear on the casing, and motion transmitting connections between the shafts of the side gears of the differential gearing and the carriage and the pusher respectively.

4. In a machine for freezing confections comprising a freezing chamber through which moulds containing confections to be frozen are

passed horizontally from a receiving station to a discharge station, a carriage at the receiving station shiftable vertically for lowering moulds with fluid confection therein into the freezing chamber, a horizontally movable pusher at the receiving station and located to push against the moulds and move them horizontally off the carriage when the latter is in its lowered position and push the moulds against the preceding moulds pushed from the carriage, a cylinder and piston motor, motion transmitting means operated by the piston rod of the motor to alternately operate the carrier and the pusher comprising a differential gearing which comprises a rotatable casing, side gears mounted on shafts journaled in the casing and differential gears in the casing and meshing with the side gears, motion transmitting connections between the piston rod and the casing to rotate the latter, motion transmitting connections between the shaft of one side gear and the carriage, motion transmitting connections between the shaft and the other side gear of the carriage, and reversing valve means operable to control the flow of motive fluid to and from opposite ends of the cylinder.

5. In a machine for freezing confections comprising a freezing chamber through which moulds containing confections to be frozen are passed horizontally from a receiving station to a discharge station, a carriage at the receiving station shiftable vertically for lowering moulds with fluid confection therein into the freezing chamber, a horizontally movable pusher at the receiving station and located to push against the moulds and move them horizontally off the carriage when the latter is in its lowered position and push the moulds against the preceding moulds pushed from the carriage, and actuating mechanism comprising a reciprocating prime mover, and motion transmitting means operable thereby to alternately operate the carrier and the pusher comprising a differential gearing which comprises a rotatable casing, side gears mounted on shafts journaled in the casing and differential gears in the casing and meshing with the side gears, motion transmitting connections between the prime mover and the casing to rotate the latter, motion transmitting connections between the shaft of one side gear and the carriage, motion transmitting connections between the shaft of the other side gear and the pusher, and means operated by the rotation of the shaft of one side gear to stop the rotation of the shaft and its side gear when rotated a predetermined distance, whereby the rotary motion of the casing is transferred to the other side gear.

6. In a machine for freezing confections comprising a freezing chamber through which moulds containing confections to be frozen are passed horizontally from a receiving station to a discharge station, a carriage at the receiving station shiftable vertically for lowering moulds with fluid confection therein into the freezing cham-

ber, a horizontally movable pusher at the receiving station and located to push against the moulds and move them horizontally off the carriage when the latter is in its lowered position and push the moulds against the preceding moulds pushed from the carriage, and actuating mechanism comprising a reciprocating prime mover, and motion transmitting means operable thereby to alternately operate the carrier and the pusher comprising a differential gearing which comprises a rotatable casing, side gears mounted on shafts journaled in the casing and differential gears in the casing and meshing with the side gears, motion transmitting connections between the prime mover and the casing to rotate the latter, motion transmitting connections between the shaft of one side gear and the carriage, motion transmitting connections between the shaft of the other side gear and the pusher, a latch coacting with the motion transmitting connections to the carrier to hold the carrier from return movement out of its lower position, and a trip for the latch on the motion transmitting connections to the pusher located to trip the latch when the pusher reaches starting position.

7. In a machine for freezing confections comprising a freezing chamber through which moulds containing confections to be frozen are passed horizontally from a receiving station to a discharge station, a carriage at the receiving station shiftable vertically for lowering moulds with fluid confection therein into the freezing chamber, a horizontally movable pusher at the receiving station and located to push against the moulds and move them horizontally off the carriage when the latter is in its lowered position and push the moulds against the preceding moulds pushed from the carriage, and actuating mechanism comprising a reciprocating prime mover, and motion transmitting means operable thereby to alternately operate the carrier and the pusher comprising a differential gearing which comprises a rotatable casing, side gears mounted on shafts journaled in the casing and differential gears in the casing and meshing with the side gears, motion transmitting connections between the prime mover and the casing to rotate the latter, motion transmitting connections between the shaft of one side gear and the carriage, motion transmitting connections between the shaft of the other side gear and the pusher, stop means coacting with the shaft of the side gear which actuates the motion transmitting connections to the carriage to hold it from rotation when the other side gear is actuating the pusher and means operated by the motion transmitting connections from said other side gear to the pusher to release the stop means when the pusher reaches starting position.
